UNITED STATES PATENT OFFICE.

FREDRICK W. SMITH, OF CHICAGO, ILLINOIS.

IMPROVEMENT IN PAPER BOXES.

Specification forming part of Letters Patent No. 147,697, dated February 17, 1874; application filed September 25, 1873.

To all whom it may concern:

Be it known that I, FREDRICK W. SMITH, of Chicago, county of Cook and State of Illinois, have invented certain new and useful Improvements in Paper Boxes; and do hereby declare that the following is a full, clear, and exact description thereof, reference being had to the accompanying drawings making a part of this specification.

Figure 1 represents a perspective view of the packet or box with the lids opened. Fig. 2 represents a perspective view of the same with the lids closed. Fig. 3 represents the form of the sheet which the packet is made of. Fig. 4 represents a cross-section of the box, taken through line $x x$, Fig. 1.

The nature of my invention consists in the construction of a packet or box, made of pasteboard or stiff paper, for containing spices, sugar, coffee, and other articles, as will be more fully hereinafter set forth.

In the accompanying drawings, A represents the sheet which forms the body of the packet. This sheet is cut in oblong or square form, having at the top two short projecting strips, C C, and one longer projecting strip, C' C'', which is between and separated from the strips C C, as shown in Fig. 3. The strip A is creased from top to bottom, as shown in dotted lines in Fig. 3, so that a wing, B B', is left at each end. The packet is formed by bending the sheet A around, so that the parts marked B'' B'' form the ends, the part B' forms the front, the central part A' forms the back, the part B folds within or behind the part B', and the parts C C form short lids, and the part C' C'' forms the top or main lid. A piece, G, is then

put in and forms the bottom of the box. A strip, E, is put in between the two parts B and B', which piece does not extend to the top, but leaves a narrow space, a, as shown in Fig. 4. The parts, after being folded together, are pasted or glued. An exterior covering of thin paper is then put on to give the box a neat finish. The packet is filled with the material desired, and the two flaps C C folded down on the same. The lid C' is then brought down, so that the wing C'' passes into the recess a. A string, D, is run around the edges of the top, leaving the ends protruding. A covering or cap of thin paper, C'', is then pasted over the lid and string, so that when the box is to be opened it is only necessary to draw the cord, tear the thin paper cap, and open the lids.

A packet thus formed can be easily manufactured, cheaply made, and readily opened without destroying the packet, and thus allow it to be reused.

In some cases I may dispense with the cross-lids C C, if so desired.

Having thus fully described my invention, what I claim, and desire to secure by Letters Patent, is—

As an article of manufacture, the packet A, made of pasteboard or stiff paper, in the form described, with the parts A' B B' B'' B'', lid C' C'', strip E, recess a, and bottom G, all constructed substantially as and for the purposes set forth.

FREDRICK W. SMITH.
